ELECTRON TUBE

Felix Herriger, Berlin, Germany, assignor to C. Lorenz Aktiengesellschaft, Berlin-Tempelhof (Germany) Lorenzweg, a company

Application September 10, 1938, Serial No. 229,245
In Germany September 13, 1937

4 Claims. (Cl. 250—27.5)

In the manufacture of electron tubes intended for very high frequencies, especially for a wave range below 3 meters, it is found that the self-capacities of the electrodes and the inductances of the leads to the electrodes assume values so high that practically it is not possible for oscillations to be amplified, the feed-back coupling effected by the inter-electrode capacities causing undesired oscillations to arise through self-excitation.

In order to avoid such self-excitation it has been proposed to arrange neutralization condensers within the vacuum vessel. By this means, however, an inductive drop of potential along the cathode leads is occasioned, whereby the symmetry effected by the neutralization condensers is undone.

In order to overcome this drawback the invention proposes to arrange two electrode systems adapted for push-pull operation and two neutralization systems in one discharge vessel common to them. A special advantage obtained in this way is that the leads to the cathodes carry merely direct current.

In accordance with another feature of the invention the neutralization systems are preferably in the nature of cold electrode systems.

The invention will be understood from the following description, reference being had to the accompanying drawing in which

Fig. 1 shows the circuit arrangement of the electrode systems, Fig. 2 represents a somewhat diagrammatic longitudinal section through an example of electron tubes as provided by the invention, Fig. 3, drawn to a larger scale than Fig. 2, shows a section on line 3—3 of Fig. 2, Fig. 4 is a diagrammatic detail view of a cathode arrangement adapted for tubes of the novel type, Fig. 5 is a fragmentary plan, viewed in the direction of the arrow, of the cathode arrangement represented in Figs. 2 and 3. Fig. 6 is a longitudinal sectional view of the electrode structure of the tubes shown in Fig. 2, taken at right angles to Fig. 2.

In Fig. 1 all of the component capacities and component inductances, contained in tubes as provided by the invention, are represented. I, II denote the component capacities of the heated electrode systems, while III, IV indicate the component capacities of the cold electrode systems that serve as neutralization systems. Each of these parts I to IV comprises the grid-anode capacity C_{ga} , the grid-cathode capacity C_{gc} and the anode-cathode capacity C_{ac} . The inductances of the grid leads are designated L_g . The

inductances of the anode leads are denoted by L_a while those of the cathode leads are designated L_c . The electrode systems of the tube are controlled over a coil A whereas the output power is taken over a coil B of a single anode circuit. The single cathode-lead is earthed at E. The arrangement here shown is perfectly neutralized in itself, so that no self-excitation of oscillations shall be possible. Also, no high frequency current will flow in the cathode lead earthed at E.

In a vacuum vessel 1 two cathodes 2, 3, two grids 4, 5 and two anodes 6, 7 are arranged in the manner illustrated in Figs. 2, 3 and 6. The cathodes are strip-shaped or flat and are parallel to the anodes 6, 7. As shown in Figs. 3 and 5, cathode 2 has an emissive layer 18. Fig. 5 also shows the cathode 3 to be provided with an emissive layer 19. The layers 18, 19 are located on opposite sides of the axis of vessel 1.

This electrode system involves the capacity distribution represented in Fig. 1, that is to say, cathode 2, grid 4 and the appertaining parts of the anodes 6, 7 correspond to the parts I, III, Fig. 1. One side of this component system, namely the side in which the emissive layer 18 is effective, forms the heated electrode system while the other or opposite side thereof forms the cold system which serves for neutralization.

The arrangement here disclosed by way of example has the special advantage that the control grid and the appertaining grid portions acting as neutralization condenser are directly interconnected, the connecting conductors thus having practically no self-induction. This effect is increased by the grids being formed as coils the turns of which are substantially vertical to the axis of the cathodes 2, 3.

Accordingly cathode 3, grid 5 and the appertaining parts of the anodes 6, 7 are arranged to act as the parts II, IV, Fig. 1.

The grid voltages are supplied from coil A, Fig. 1, over leads 8, while the anode currents are taken through leads 9. In order to effect a continuous transition of the surge impedance from the anodes 6, 7 to the leads 9, the points at which these leads are joined to the anodes are fitted with a sheet metal covering 10.

In the manufacture of the arrangement here described the leads 8, 9 are fixed in a ceramic ring 11 in the direction of radii. Then the said electrode systems are arranged and two glass hoods 12 are secured to ring 11. In the vessel 1 thus formed the electrode systems are held in place by means of insulating discs 13, 14, for

instance. In order that in the case of high power tubes a directly heated cathode can be employed, a second wire-shaped cold cathode 16 is added to a heated cathode 15, the two being arranged to cross in the middle, as represented in Fig. 4. Cathode 16 is to prevent the emission current from being controlled by the neutralization system. Similarly, the screening between the heated system and neutralization system may be effected by a suitable piece of sheet metal. Also, the two grid-cathode systems may be located beside each other, the cathodes then having to be interconnected by short conductors. In the case of high power tubes the anodes may be hollow bodies and two hollow leading-in members may be attached to the anodes in order to provide for cooling these by circulatory water. If such water cooling is employed, the entire electrode system may be arranged in a closed ceramic vessel.

The neutralization systems instead of being in the nature of cold electrode systems as here before described, may be composed of condensers and coils.

A screening 17 of sheet metal may be arranged to surround the leads 8 in the manner appearing from Fig. 3, such screening being of cathode potential.

What is claimed is:

1. An electron tube comprising a first cathode and a second cathode, a first anode facing a first surface of both said cathodes, a second anode facing a second surface of both said cathodes, a first grid coiled around one of said cathodes, a second grid coiled around the other of said cathodes, and means to prevent electron current from flowing between said first surface of said first cathode and said second anode and between said second surface of said second cathode and said first anode.
2. An electron tube according to claim 1 wherein said first and second cathodes are emissive on their second and first surfaces respectively and are non-emissive on their other surfaces, and wherein said cathodes are adapted by their dimensions to prevent the electric fields of said first and second anodes from influencing the electron flow from said first and second surfaces respectively.
3. An electron tube as defined in claim 1, wherein the cathodes are strip-shaped, and are indirectly heated, only one side thereof being provided with emissive layer.
4. An electron tube according to claim 1, having non-heated screening means adapted to protect the cathodes from being influenced by the fields of the neutralization systems.

FELIX HERRIGER.
